SPRING SPREADER

Edward M. Pfauser, Elm Grove, Wis., assignor to
 Blackhawk Mfg. Co., Milwaukee, Wis., a corporation of Wisconsin

Application January 9, 1939, Serial No. 249,887

2 Claims. (Cl. 29—87.1)

This invention relates primarily to improvements in the construction and operation of apparatus for spreading leaf springs in order to facilitate removal and insertion of the spring hanger pins coacting with the opposite spring ends.

An object of the present invention is to provide a new and useful spring spreading assemblage which is simple in construction and highly efficient in use.

It has heretofore been common practice in the automobile industry, to utilize fluid pressure actuated jacks or rams for the purpose of spreading the opposite ends of relatively stiff vehicle body supporting leaf springs, in order to permit convenient insertion and removal of the spring hanger pins or shackle studs at the springs ends. The type of hydraulic jack ordinarily utilized for this purpose, comprises generally a cylinder having a plunger slideable therein and projecting outwardly through the open cylinder end, and an elongated extension projecting away from the opposite closed end of the cylinder in line with the plunger. This jack assembly may be disposed between the pin or stud receiving loops formed integral with the opposite ends of the spring, and wedge shaped fittings are usually interposed between the outer ends of the jack plunger and extension, and the adjacent spring end loops in order to prevent the jack from becoming displaced while the spring is spread. The wedge portions of the retainer fittings heretofore employed, were off-set relative to the common axis of the cylinder, plunger, and extension, and also with respect to the axes of the shackle studs, and when spreading force was applied by the jack, this off-set disposition of the wedges would subject the elongated jack assembly to enormous transverse stresses and would in many cases actually bend the jack elements laterally and cause permanent distortion thereof.

It is therefore a more specific object of my present invention, to provide an improved fitting adapted for disposition between the spring ends and a spreader jack for leaf springs, which will relieve the jack from undesirable lateral stresses while at the same time preventing the jack assemblage from being displaced while the spring is being spread.

Another specific object of the invention is to provide a spring spreader fitting which is especially adapted for coaction with the looped ends of leaf springs, and which may be applied as an

attachment to relatively standard jack assemblies.

A further specific object of this invention is to provide an improved spring spreading assemblage which can be readily applied and manipulated, and which may be manufactured at moderate cost.

These and other specific objects and advantages will be apparent from the following detailed description.

A clear conception of an embodiment of my present invention, and of the mode of utilizing the improvement to effect spreading of leaf springs, may be had by referring to the drawing accompanying and forming a part of this specification in which like reference characters designate the same or similar parts in the several views:

Fig. 1 is a part sectional side elevation of a 20 spring and spreader jack assemblage, showing the jack in section and in the act of spreading the leaf spring;

Fig. 2 is an enlarged top view of one of the improved spreader fittings;

Fig. 3 is a longitudinal vertical section through the fitting of Fig. 2, taken along the line 3—3; and

Fig. 4 is a similarly enlarged end view of the fitting.

While I have shown and described the improved appliance in conjunction with a particular type of hydraulic jack, it is not the intent to thereby unnecessarily restrict the scope or utility of the invention.

Referring to the drawing, in the assemblage of Fig. 1, a standard multiple leaf spring 6 has opposite looped ends 7, 8 formed integral with the upper leaf, and adapted for reception of shackle studs 9. The several leaves of the spring 6 are

40 normally held together by retainer straps 10, and the lower portion of the spring, midway between the looped ends 7, 8 normally rests upon and is attached to the vehicle axle, while the studs 9 are carried by links suspended from the body of the vehicle, in a well known manner.

The hydraulic ram or jack which is shown rather diagrammatically, comprises a cylinder 11 having a plunger 12 slideable therein and projecting outwardly through the open end thereof, and 50 a duct 13 for admitting liquid to and for exhausting the liquid from the cylinder 11. An elongated extension 14 is secured to and projects away from the opposite closed end of the cylinder 11, in line with the plunger 12, and the outer ends of the plunger 12 and extension 14 are

threaded for the reception of my improved fittings. This hydraulic jack assemblage is also old and well known, and the overall length of the jack may be varied by replacing the extension 14 with a longer or shorter similar element.

My improved spring spreader fitting 15 is shown in detail in Figs. 2, 3 and 4, and each of these fittings 15 has an internally threaded socket 16 at one end adapted for firm but detachable attachment to the adjacent threaded end of the plunger 12 or extension 14. The opposite end of each fitting 15 is provided with a laterally extending elongated V-shaped concavity 17 which is interrupted intermediate its ends by a central notch 18 disposed in line with the axis of the socket 16, and the two end portions of the fitting are rigidly interconnected by side ribs 19 and a stiff web 20.

When the fittings 15 have been applied to a jack assemblage and positioned between the looped ends 7, 8 of a leaf spring 6 as in Fig. 1, and the jack is expanded by admitting liquid under pressure to the cylinder 11 through the duct 13, the fittings 15 carried by the outer extremities of the plunger 12 and extension 14 will be forced into engagement along the concavities 17 with the spring ends 7, 8. By virtue of the V-shape of the concavities 17, and due to the provision of the notches 18, the outer ends of the fittings 15 will readily find bearing line or point contact at several places, upon the spring end loops, regardless of irregularities existing on the adjacent surfaces of the loop ends 7, 8. Because of the fact that the fittings 15 have screw thread attachment with the plunger 12 and extension 14, these fittings may also rotate slightly about the longitudinal jack axis during initial application of spreading force, thus also insuring proper seating of the concavities 17 against the loop ends 7, 8. As additional hydraulic pressure is applied to the jack and the plunger 12 moves outwardly, the spring ends 7, 8 will be forced apart and the lateral pressures to which the studs 9 are normally subjected, will be gradually released. The studs 9 may then be freely withdrawn from the loop ends 7, 8 while the spring 6 is retained in spread condition by the jack assembly, and the pins or studs 9 may obviously be just as easily returned or reinserted within the loops.

It will be apparent from the foregoing description, that the symmetrical formation and central disposition of the V-shaped concavities 17 of the improved fittings 15, in true alignment with the axis of relative movement of the plunger 12 and extension 14, prevents the jack elements from being subjected to undesirable lateral stresses which tend to bend these parts. This is true regardless of variations in the fixed sizes or diam-

eters of the loop ends 7, 8, one of which may be smaller than the other, since the fittings coact with the loops on opposite sides of the common plane of the jack axis and of the shackle pin axes. The angular concavities 17 aided by the notches 18 will insure proper cooperation between the fittings 15 and the spring loops, even if central pins are used to normally hold the studs 9 in place, and the threaded sockets 16 of the fittings 15 also assist in assuring such proper cooperation. The fittings 15 themselves are prevented from bending by the side ribs 19 and web 20, and the improved fittings have proven highly successful in actual use and may obviously be manufactured at extremely moderate cost. These fittings 15 are moreover very simple in construction and may be readily utilized by a novice, and there is no danger of undesirable dislocation of the spreading assemblage when the fittings have been brought into initial proper location and coaction with the spring ends 7, 8.

It should be understood that it is not desired to limit this invention to the exact details of construction or to the precise mode of use, herein shown and specifically described, for various modifications within the scope of the claims may occur to persons skilled in the art.

I claim:

1. A spreader assemblage for leaf springs having pin engaging circular end loops, said assemblage comprising, a jack having relatively separable opposite end portions disposable between the spring loops and movable along an axis disposed in the common plane of the loop axes, and fittings interposed between said jack end portions and the adjacent spring loops, each fitting having a transverse concavity formed symmetrical relative to said plane and engaging the adjacent spring loop on opposite sides of said plane so as to confine said jack portions to relative movement along the jack axis and in said plane.

2. A spreader assemblage for leaf springs having pin engaging cylindrical end loops, said assemblage comprising, a jack having relatively separable coaxial opposite end portions disposable between the spring loops and movable along an axis disposed in the common plane of the loop axes, and fittings rotatable about said jack axis and coacting with said spring loops, each fitting having a V-shaped transverse concavity formed symmetrical relative to said plane and engaging the adjacent spring loop on opposite sides of said plane so as to confine said jack portions to movement along the jack axis and in said plane.

EDWARD M. PFAUSER.
